(57) **CLAIM**

The ornamental design for a health assessment kiosk, as
shown and described.

DESCRIPTION

FIG. 1 is a front, top and side perspective view of a health
assessment kiosk, showing our new design;

FIG. 2 is a front elevation view thereof;

FIG. 3 is a rear elevation view thereof;

FIG. 4 is an elevation view thereof from the side opposite
that in FIG. 1;

FIG. 5 is an elevation view thereof from the same side as in
FIG. 1;

FIG. 6 is a top plan view thereof; and,

FIG. 7 is a bottom plan view thereof.

The portions of the health assessment kiosk shown in broken
lines is for illustrative purposes only and form no part of the
claimed design.
